UNITED STATES PATENT OFFICE

147,505

DESIGN FOR A LAPEL ORNAMENT OR SIMILAR ARTICLE

Janice Mourar, Missoula, Mont.

Application July 1, 1946, Serial No. 131,239

Term of patent 3½ years

(Cl. D45—19)

To all whom it may concern:

Be it known that I, Janice Mourar, a citizen of the United States of America, residing at Missoula, in the county of Missoula and State of Montana, have invented a new, original, and ornamental Design for a Lapel Ornament or Similar Article, of which the following is a specification, reference being had to the accompanying drawing, forming part thereof.

In the drawing:

Fig. 1 is a front view of a lapel ornament illustrating my new design; and
Fig. 2 is a side view thereof.

I claim:

The ornamental design for a lapel ornament or similar article, as shown.

JANICE MOURAR.
